UP-SKI TOWING DEVICE

George V. Dondero, San Francisco, Calif.

Application May 12, 1939, Serial No. 273,277

4 Claims. (Cl. 104—202)

This invention relates to an improvement in up-ski towing apparatus and more particularly to a new and novel form of tow rope gripping means by which a skier can place himself in towing relation with a tow rope in a simple and convenient manner.

A further object of the invention is to provide a new and novel form of rope gripping means for the tow rope of an up-ski towing system in which, after connection with the tow rope, the user's hands will be free and thus permit the carrying and/or use of ski-poles in a normal manner.

Another object of the invention is to provide a small, compact and simple grip forming device for use with an up-ski tow line which can be conveniently and securely carried in an unobstructing manner beneath the belt of a skier when not in use.

Another object of the invention is to provide a tow-line gripping device which will effectively grip the tow rope when in its normal operating position and which will automatically become disengaged from the tow rope when in an abnormal position.

In the early days of up-ski towing equipment it was customary to provide nothing more than a tow rope which the skiers could grasp with their hands. This arrangement however was soon found objectionable for the reason that the rope often became wet or icy and hard to grip with heavily mitten hands. Another serious objection to this type of up-ski towing equipment was that it required the use of both hands and caused the skier to assume an unnatural position. It was also difficult for the skier to carry other equipment, such as ski-poles, to the top of the hill and therefore at best it provided only a difficult and tiring expedient. To remedy this situation many complicated up-ski towing systems have been provided in which a chair or permanently affixed sling or hook attached to the tow rope is used to carry or tow the skier to the top of the hill. In these systems the skier is required to release himself or jump clear so as to permit the permanently affixed chair, hook or sling to pass around or over a sheave at the upper end of the tow line and thus proceed down to the bottom of the hill for further use. These devices require considerable agility on the part of the users and often the use of an attendant to prevent injury to the skier. Therefore, it has become more and more desirable to provide a simple arrangement for use with up-ski tow lines which can be used safely by a novice. To this

end the present invention contemplates the provision of a simple rope gripping device which may be permanently secured in a non-rigid manner by a short tow cord to the body of a user and which is of such a construction that it will immediately disengage the up-ski towing rope immediately upon the release of a towing tension on the tow cord and/or in the event that the skier falls down or assumes a position with respect to the tow rope other than a normal towing position.

In Patent No. 2,079,491, granted May 4, 1937, to Theodore C. Cooke there is shown a rope gripping device having oppositely disposed and hook forming portions that are adapted when in use to grip a tow rope with a kinking action. While this device, when properly used, effectively serves its purpose, it is open to the objection that it is incapable of automatically releasing itself from the tow rope when released and as a consequence should the user for any reason lose his grip upon the device or find it impossible to impart thereto the definite forward movement required to release it from the tow rope, the device will be carried along with the tow rope and thus interfere with the free passage of the tow rope about the sheave at the end of the tow line and thus interfere with the successful operation of the system. As distinguished from this prior device, the present invention provides an up-ski tow rope gripping device that can be applied to a tow-rope in a simple manner and which is of such a character that it will automatically release and fall from the tow rope immediately upon the release of an existing pressure thereupon without requiring any special releasing maneuver on the part of the user.

For a better understanding of the invention reference should be had to the following description taken in connection with the accompanying drawing, wherein there is shown by way of illustration and not of limitation a preferred embodiment thereof.

In the drawing;

Figure 1 is a view showing the manner in which the invention is used by a skier upon a tow rope,

Figure 2 is a plan view showing the device as applied to a tow rope,

Figure 3 is an end view of the device shown in Figure 2,

Figure 4 is a side view of the device shown in Figure 2,

Figure 5 is a horizontal sectional view taken along line V—V of Figure 4, and

Figure 6 is a fragmentary view showing the

55

rope gripping device attached to the body of the wearer and as it is carried during the downhill run.

In Figure 1 of the drawing the gripping device, designated generally by the numeral 10, is shown as applied to a tow rope 11 that is moving in an uphill direction, as indicated by the arrow adjacent thereto. The gripping device 10 has a short tow cord 12 that is preferably secured to a belt 13 worn by a skier here shown as upon skis 14. With this arrangement it will be seen that when the device 10 is thus in use with the ski-rope 11 the arms of the skier will be free to use ski-poles 15 in maintaining a proper direction of travel and balance.

As shown in Figures 2, 3, 4 and 5 of the drawing, when the gripping device 10 is constructed in accordance with the preferred form of the present invention, it comprises a rope spanning member or portion 16 having upstanding oppositely disposed side portions or ears 17 and 18 that in effect form a channel through which the tow rope 11 is adapted to extend. Extending outwardly to one side and at an angle at the forward end of the upstanding side portions 17 and 18 the member 10 is provided with a lever arm 19 having an eye 20 to which the tow cord 12 is tied. With this arrangement, when a towing tension is placed upon the tow cord 12, the lever arm 19 will exert a canting action upon the rope spanning portion 16 of the device 10 and thus bring the oppositely disposed ends of the upstanding portions 17 and 18 thereof into gripping engagement with the tow rope 11, as is clearly illustrated in Figure 2 of the drawing. At this point it should be observed that the channel formed between the upstanding portions 17 and 18 of the grip forming member 10 is such that the rope 11 will fit loosely therein. This permits the gripping device 10 to fall and thus become immediately disengaged from the tow rope 11 whenever a towing tension is not maintained upon the tow cord 12.

In order to provide for a more positive gripping action between the opposed upstanding portions 17 and 18 and the rope 11 and also avoid the necessity for manually holding the gripping device 10 upon the rope 11 during the starting and/or other periods of low tension upon the tow cord 12, as for example on a substantially level path, the upstanding portions 17 and 18 may if desired be provided with a slight undercutting 21 and 22 respectively at their trailing and forward edges, as is illustrated in Figures 3 and 5 of the drawing. This undercutting of the upstanding portions 17 and 18, however, is not of any such magnitude as to prevent a free falling away of the gripping device 10 from the tow rope 11, as suggested above, whenever towing tension is removed from the tow cord 12.

While the device is illustrated in Figure 1 of the drawing with the skier on the left-hand side of the tow rope 11 and with the rope spanning portion 16 extending beneath the tow rope, it will be understood that the gripping device 10 is equally effective when the skier is on the right-hand side of the tow rope 11 with the spanning portion 16 of the device 10 extending over the top of the rope. In other words, it is immaterial whether the gripping device 10 engages the tow rope 11 from the bottom or the top side thereof as the weight and forward disposition of the lever arm 19 with respect to the leading edges of the rope engaging portions 17 and 18 effectively cooperate to form what may be termed

a weighted lever which will tip the rope engaging portions 17 and 18 and thus disconnect the gripping device from the tow rope whenever the towing pressure is released therefrom or is applied in an abnormal direction.

5

As shown in Figure 6 of the drawing, it is contemplated that each skier will provide himself with his own gripping device 10 and therefore the device can be permanently attached to the skier. This is most conveniently accomplished by attaching the rear end of the tow cord 12 to a slidible band 23 through which a belt 24 worn by the skier may be passed. When the device 10 is thus attached to the belt of a skier it can be conveniently carried during the downhill run by inserting the tow rope engaging end thereof beneath the belt 24 in the manner shown with the arm 19 thereof held closely against the body of the skier and in a position where it will not interfere with the free movement of the skier. A further advantage of this arrangement is that the device 10 cannot become misplaced or lost in the snow.

As a safety precaution it is also contemplated that the tow cord 12 may be of relatively light cord so that in the event of an excessive strain thereupon, due to any unforeseen obstruction in the path of the skier, it will break and thus permit the gripping device 10 to fall from the tow cord 12. Instead of having a fragile cord 12, it is also possible to obtain this advantage by providing a fragile or self-releasing connection between the tow cord 12 and the belt 24 of the wearer.

While I have, for the sake of clearness and in order to disclose my invention so that the same can be readily understood, described and illustrated a specific device and arrangement, I desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is—

1. In a gripping device for up-ski towing systems, the combination of a grip forming member of U-shaped cross-section having its sides spaced to form an open channel for the reception of a tow rope, a lever forming arm extending laterally of the rope and from the forward end of said channel, said lever forming arm being disposed in line with the bottom of said channel and operable in a plane tangent to the surface of the tow rope when in use, and a tow cord carried by the free end of said lever adapted to form a non-rigid connection between the end of said lever and the body of a skier, whereby said grip forming member will be canted and kink said tow rope when a normal towing tension is exerted upon said tow cord and disengage said tow rope when other than a normal towing tension is exerted upon said tow cord.

2. A gripping device for up-ski towing systems, comprising a loose fitting grip forming member of U-shaped cross-section having its sides spaced to form a channel for the reception of a tow rope, a lever forming arm extending outwardly at an angle from the leading end of said channel, a tow cord carried by the outer end of said lever forming arm adapted to provide a non-rigid connection between the end of said lever and

65

70

75

80

- and the body of a skier, said lever forming arm being disposed in line with the bottom of said channel and operable in a plane tangent to the surface of the tow rope when in use, whereby
- 5 the sides of said grip forming member will be canted into kinking relation with the tow rope when a normal tension is exerted through said tow cord and tipped out of gripping relation with the tow rope when other than a normal or
- 10 no towing tension is exerted through said tow cord.
3. A gripping device for up-ski towing systems, comprising a grip forming member of U-shaped cross-section having its sides spaced to form a
- 15 loose fitting channel for the reception of a tow rope, a lever forming arm extending outwardly at an angle from the leading end of said channel, a tow cord carried by the outer end of said lever forming arm adapted to provide a non-rigid
- 20 connection between the end of said lever and the body of a skier, said lever forming arm being disposed in line with the bottom of said channel and operable in a plane tangent to the surface of the tow rope when in use, whereby
- 25 the sides of said grip forming member will be canted into kinking engagement with the tow rope when a normal tension is exerted through said tow cord and when no towing tension is exerted through the tow cord said forwardly and

outwardly extending arm will operate as an off center weight and tip the sides of the grip forming member out of kinking relation with the tow rope.

4. A gripping device for up-ski towing systems, comprising a rope spanning member having spaced side portions forming a loose fitting channel through which a tow rope is adapted to extend, a lever forming arm extending outwardly at a leading angle from the forward end of one of said side portions, and a tow cord carried by the outer end of said lever forming arm adapted to provide a non-rigid connection between the end of said lever forming arm and a skier, said lever forming arm being located in line with the bottom of the rope receiving channel formed by said spaced side portions and operable in a plane tangent to the surface of the tow rope when in use, the trailing end of the side portion adjacent said lever forming arm and the leading end of the other of said side portions being undercut to form a curved tow rope engaging surface at these points, whereby the off center disposition of the lever forming arm with respect to the axis of the tow rope will not result in a displacement of the grip forming member when a normal towing tension is exerted through said tow cord.
